UNITED STATES PATENT OFFICE.

JOHN F. DOOLITTLE, OF CLEVELAND, OHIO.

SHEARS FOR BARS OF STRUCTURAL SHAPES.

SPECIFICATION forming part of Letters Patent No. 746,800, dated December 15, 1903.

Application filed June 6, 1902. Serial No. 110,552. (No model.)

To all whom it may concern:

Be it known that I, JOHN F. DOOLITTLE, a citizen of the United States, residing at Cleveland, in the county of Cuyahoga and State of Ohio, have invented certain new and useful Improvements in Shears for Bars of Structural Shapes, of which the following is a specification.

This invention relates to machines and apparatus therefor employed for cutting off bars of metal, and especially for severing by shearing or punching bars or beams of steel or iron of the various cross-sections commonly termed "structural shapes."

The object of the present invention is to provide means and attachments for adapting shearing or punching machines of the usual type for cutting off bars or beams of any of the common structural shapes or sizes without the necessity of changing the machine or its attachments. It has been possible heretofore to punch and shear off such beams and bars by employing blades, dies, &c., formed especially to fit each size and section of bar or beam to be cut; but this method necessitates an equipment comprising many expensive attachments for each machine where, as is usually the case, many sizes and shapes are to be cut, and in addition to the cost of making and storing said attachments much time and labor is required in taking off from and fitting to the machines the respective attachments. This labor and expense is eliminated by my invention, for the machine having been fitted to cut one size or shape it will cut any other of the usual sizes or shapes of structural bars or beams without further change. A further advantage is sought to be gained by constructing the apparatus in such a way that long beams may be introduced sidewise into the machine. Minor objects will become apparent from the description and claims.

To these ends my invention consists in the novel features, arrangements, and combinations hereinafter described and claimed, an embodiment thereof as applied to a single punching and shearing machine being illustrated in the accompanying drawings, in which—

Figure I is a side elevation of a machine equipped with my invention, the rear end thereof being broken away; and Fig. II is a

front elevation of the same. Fig. III is a side elevation, and Fig. IV is a cross-section of an I-beam, and Fig. V is a cross-section of a channel-beam, showing the web portions slotted across, such being the first step in the operation of cutting off a beam. Fig. VI is a side view, and Fig. VII is an end view in section of an I-beam, and Fig. VIII is a sectional end view of a Z-bar, illustrating the second step in the said operation. Fig. IX is a front view of the "gag" arrangement employed.

The reference-letter *a* represents the frame of a punching and shearing machine of the ordinary type, having a shaft at *b*, which is rotated by any suitable means and by any available power. The main shaft *b* extends through the front of the frame to operate a vertically-reciprocating slide-block or plunger *c* by means of a crank or eccentric formed in the shaft operating a short connecting-rod *d*, Fig. IX, the lower end of said rod being journaled in a suitable bearing-block *e*, arranged to reciprocate vertically in the plunger. The plunger *c* is provided with a counterweight *f*, adapted to hold it normally against a suitable stop at the upper end of its stroke, in which position it is shown in Figs. I and II.

The bearing-block *e* has a flat under surface, and an opening of considerable depth is formed in the plunger under said block, so that the block may reciprocate without driving the plunger. In the front face of the plunger a shear-blade holder *g* is fitted, and in the rear face thereof is a punch-holder *h*, both of which holders are fitted to slide vertically and both being provided with flat topsurfaces and with lateral flanges, as at *i*, to rest upon shoulders formed in the plunger, as shown in Figs. I, III, and IX. The holder *g* carries a shear-blade *j*, which is preferably stepped upon its lower edge, as shown in Fig. I, in order that the shearing operation may be accomplished with a short stroke; but said blade may have its cutting edge straight and at right angles to its line of travel, as indicated in Fig. VIII, if desired, provided the stroke of the machine is long enough to permit. The holder *h* carries a flat punch *k*, which is preferably of a rectangular cross-section, having its greatest width from front to rear of the machine. A corresponding die is set under said punch in

a holder *l*, raised above the bed of the machine.

Secured in a suitable holder *m*, attached to the bed of the machine, are two lower shear-blades *n*, so disposed that the blade *j* will pass down between them. A double blade made in the form of a die may be employed instead of two separate blades, if desired. These lower blades have their cutting edges formed at an angle of about forty-five degrees, more or less, with the line of travel of the upper blade. They are also provided with an offset at *o*, the purpose of which will be explained hereinafter.

15 A rectangular block *p*, commonly termed a "gag," is fitted to be thrust in between the bearing-block *e* and the shear-holder *g*. Another gag-block *q* is similarly arranged between the block *e* and the punch-holder *h*. 20 These gag-blocks each have handles projecting through vertical slots in the side of the machine, and recesses are provided for them in the side of the plunger, so that they may be respectively drawn out from under the block *e*. Thus it will be seen that by thrusting the gag *p* in under the block *e* the plunger *c* will be reciprocated downward by said block, carrying with it the shear-holder *g*. Likewise by thrusting in the gag *q* the punch will 25 be operated.

30 A cord or cable *r* is secured to the shear-holder *g*, as shown, passing over suitable pulleys, such as *s*, *t*, and *u*. A counterweight (not shown) is attached to the cord *r*, depending from the pulley *u*, and serves to overbalance the shear blade and holder *g*, so that when the gag *p* is pulled out the shear-blade and holder will be raised up by said weight into the plunger, thus leaving the throat of 40 the machine clear for the introduction of the beams or bars to be cut. The punch and its holder *h* may also be raised up into the plunger, and a notch *v* in the gag *q* may be provided to engage one of the lateral flanges *i* 45 of the punch-holder and support the latter in its raised position.

45 Fitted to slide into the throat of the machine over the bed thereof, resting upon and guided by suitable ways, such as *x*, is a table *w*, which overhangs the machine on each side, being made long enough to present an adequate support to the beams to be cut. Said table carries upon its upper face a rigid upright rib or stop *y* and a movable stop *z*, 50 between which a beam to be cut—such, for example, as that indicated at 1—may be held. The front part of said table is inclined downward at the same angle as that of the lower shear-blades, and at the rearward position of 55 the table the upper face of said inclined portion should be approximately flush with the cutting edges of said lower blades. Stakes or pins *2* of varying lengths are provided, which may be inserted in suitable apertures 60 in the inclined portion of the table to support the beam during the shearing operation.

To cut off a beam or bar, the procedure is

first to draw out both gag-blocks, permitting the upper shear-blade to rise and then to raise the punch so that the beam may be introduced sidewise into the throat of the machine. The beam is then laid upon the sliding table against the stop *y* and the stop *z* is brought forward against it. The table is moved preferably, but not necessarily, to its rearward position, as in Fig. I. The shaft *b* being in rotation, the punch *k* is put into operation by inserting the gag *q*. After one punching is made in the beam the table is moved forward, and so on until a slot is 80 punched entirely across the web of the beam, as shown in Figs. III, IV, and V. The operation of the punch *k* is then stopped by removing the gag and the beam is moved forward to the position shown in dotted lines in Fig. I, resting upon the inclined front of the table and the stakes *2*. In this position it will be noticed that the lower flange or corner of the beam or bar rests against the offset *o* in the lower shear-blades and is rigidly held 90 thereby from sliding down the inclined faces of the blades. The shear-blade *j* is then centered over the slot in the beam, and the gag *p* being thrust in the flanged side of the beam is sheared through, as indicated in Figs. 95 VI, VII, and VIII. It is then only necessary to turn the beam over and shear through the other side in the same way to complete the operation.

100 It is obvious that the leading principles of construction and modes of operation of the invention may be embodied in two machines instead of the single machine above described, although the latter is preferable; but conditions of installation might arise where 105 it would be desired to use one machine fitted with the punch *k* and the sliding table *w* for slotting the webs of beams, and to employ another machine equipped with the shear-blades *j* and *n* and a suitable inclined support in lieu of the front of the table *w* for shearing off the flanges of beams.

110 Other modifications may be made without departing from the spirit of my invention, and change may be made in the details of the 115 mechanism disclosed, provided the principles of construction set forth respectively in the following claims are employed.

I therefore particularly point out and distinctly claim as my invention—

1. In machines for cutting off bars or beams, the combination of mechanism suitable for punching a slot across the web portion of a beam or bar, and means for shearing or punching the flange or side portions of said beam 125 or bar comprising fixed parallel shear-blades set at an oblique angle to the line of travel of the movable shear-blade, a movable shear-blade adapted to travel in a straight line and reciprocate between said fixed shear-blades, 130 means for holding the beam or bar upon said fixed shear-blades, and suitable mechanism for reciprocating said movable shear-blade, substantially as set forth.

2. In a machine of the class described, the combination with a punching and shearing machine, of fixed parallel shear-blades set at an oblique angle to the line of travel of the movable shear-blade, a movable shear-blade adapted to travel in a straight line and reciprocate between said fixed shear-blades and having cutting edges at right angles to its line of travel, means for holding a beam or bar upon said fixed shear-blades, and suitable mechanism for reciprocating said movable shear-blade, substantially as set forth. 65
3. In a machine of the class described, the combination with a punching and shearing machine, of fixed parallel shear-blades set at an oblique angle to the line of travel of the movable shear-blade and provided with offsets to hold a bar or beam in place thereon, a movable shear-blade adapted to travel in a straight line and reciprocate between said fixed shear-blades and having its cutting surface or surfaces at right angles to its line of travel, and suitable mechanism for reciprocating said movable blade, substantially as set forth. 70
4. In a machine of the class described, the combination with a punching and shearing machine, of fixed parallel shear-blades set at an oblique angle to the line of travel of the movable shear-blade and provided with offsets to hold a bar or beam in place thereon, a movable shear-blade adapted to travel in a straight line and reciprocate between said fixed shear-blades and having its cutting edges at right angles to its line of travel, suitable mechanism for reciprocating said movable blade, and means adapted to support said bar or beam so that a flange thereof will rest in proper position upon said fixed shear-blades, substantially as set forth. 75
5. In mechanism of the class described, the combination with a punching and shearing machine, of fixed shear-blades set parallel to each other and at an angle to the line of travel of the movable shear-blade and provided with offsets or stops for retaining a bar or beam in place thereon, supporting means for said bar or beam having surfaces inclined at the same angle as said fixed blades and provided with removable pins projecting from said inclined surfaces at right angles thereto, a movable shear-blade adapted to reciprocate between said fixed shear-blades having its cutting edges at right angles to its line of travel, and suitable mechanism for reciprocating said movable blade, substantially as set forth. 80
6. In mechanism of the class described, the combination with a punching and shearing machine provided with a suitable gag arrangement, of fixed shear-blades set parallel to each other and at an oblique angle to the line of travel of the movable shear-blade, means for retaining a bar or beam in place upon said fixed blades, a movable shear-blade adapted to be reciprocated between said fixed blades by said gag arrangement and having its cutting edges at right angles to its line of travel, a suitable holder for said movable blade, and a counterweight in operative connection with said holder adapted to raise the same and its blade clear of the throat of the machine when said blade is thrown out of operation by the removal of the gag, substantially as set forth. 85
7. In mechanism of the class described, the combination with a punching and shearing machine, of a slotting-punch and mechanism for operating it, a suitable die therefor, a sliding table upon the bed of the machine arranged to be reciprocated from front to rear of the throat thereof and adapted to hold a beam or bar and carry the same across said die, a reciprocating shear-blade having its cutting edges at right angles to its line of travel, fixed shear-blades secured to the bed of the machine having their cutting-faces set parallel to each other and at an oblique angle to the line of travel of the reciprocating blade and so disposed that the latter will pass between them, and means adapted to support a beam or bar so that the flanged side thereof will rest in proper position upon said fixed blades, substantially as set forth. 90
8. In mechanism of the class described, the combination with a punching and shearing machine, of a slotting-punch and mechanism for operating it, a suitable die therefor, a sliding table upon the bed of the machine arranged to be reciprocated from front to rear of the throat thereof and adapted to hold a beam or bar and carry the same across said die, a reciprocating shear-blade having its cutting edges at right angles to its line of travel, fixed shear-blades secured to the bed of the machine having their cutting-faces set parallel to each other and at an oblique angle to the line of travel of the reciprocating blade and so disposed that the latter will pass between them, offsets or stops in said fixed blades to engage a bar or beam to be cut, and an inclined front face upon said sliding table provided with removable pins projecting therefrom and adapted to support said bar or beam so that the flanged side thereof will rest in proper position upon said fixed blades, substantially as set forth. 95
